UNITED STATES PATENT OFFICE.

WILLIAM G. LE COMpte, OF NEW YORK, N. Y., ASSIGNOR OF ONE-HALF TO J. ODELL FOWLER, OF NEW YORK, N. Y.

HINGE.

1,167,906.

Specification of Letters Patent. Patented Jan. 11, 1916.

Application filed April 13, 1910. Serial No. 555,257.

To all whom it may concern:

Be it known that I, WILLIAM G. LE COMpte, a citizen of the United States, and a resident of New York, in the county of 5 New York and State of New York, have invented a certain new and useful Hinge, of which the following is a specification, the same being a full, clear, and exact description of the invention, such as will enable 10 others skilled in the art to which it appertains to make and use the same.

This invention relates to the articulation of two movable devices, or of an object to its support, and in particular to an artificial 15 movable joint whereby two bodies may be connected in such a manner that one may be turned upon the other and securely held in any desired position, which I call a geared friction hinge, and also to the application 20 of such a device to wind shields. The object of the latter application of the invention is to provide a wind shield, made in a plurality of sections, which are ordinarily glazed, and adapted especially for 25 use in automobiles, which sectional shield may be firmly sustained in position at any desired angle, and the upper section of 30 which may also be readily folded over so as to lie upon the lower section, and securely held in the said folded position, by means of the use of the said hinge alone.

This invention consists of a peculiar construction and arrangement of parts herein-after described and illustrated in the drawings which accompany and form a part of 35 this specification, and in which—

Figure 1 represents a front elevation of a hinge embodying my invention; Fig. 2 is a side view of the same partly in section; 40 Fig. 2^a is a view in section taken on the line 8—8 of Fig. 2; Fig. 3 is a rear elevation; Figs. 4, 4^a, 5 and 6 are views of the hinge members placed at different angles and in different positions; Figs. 7 and 8 are views 45 of the hinge casing showing the slot formed therein; and Fig. 9 is a view in section of another hinge constructed according to my invention.

Like letters of reference indicate like 50 parts in all the views.

The hinge embodying the present invention ordinarily consists of a member A having means by which it may be rotated, and by which friction may be created, preferably 55 comprising a circular or wheel-shaped part G, the periphery of which may consist

partly of a plain, or even, or smooth face, and partly of a preferably mutilated gear construction, a circular groove K being preferably located therebetween, as is represented in Fig. 2; or, if desired, the corrugations forming the gear teeth may extend entirely across the face of the part G, as shown in Fig. 9. The other member E of the hinge ordinarily has a similar means by which it may be rotated, and by which friction may be created, preferably comprising a circular or wheel-shaped part G', the periphery of which may consist partly of a plain, or even, or smooth face, and partly of a preferably mutilated gear construction, a circular groove K being preferably located therebetween, as is represented in Fig. 2; or, if desired, the corrugations forming the gear teeth may extend entirely across the face 75 of the part G', as shown in Fig. 9.

The rotating means of the members A and E may be integral therewith, in the manner the part G is shown in Fig. 2, or it may be mechanically applied thereto by being 80 screwed or otherwise fastened to the body of the member, as the part G' is represented at d.

The parts G and G' which, strictly speaking, form my hinge members, are ordinarily 85 assembled in a casing or housing B, which is preferably made integral, as by being cast in solid form, and is ordinarily bored out to form a cavity or dual-concave recesses of such size, shape and contour as 90 to register with the peripheries of the said parts G, G'. A bolt C is preferably passed through the casing in a transverse direction and serves to clamp the parts together so that the boundaries of the recesses or races 95 so formed will impinge upon and create a friction between the same and the peripheries of the rotatable parts G, G'. A somewhat resilient clamping effect may be produced by the use of a disk or washer C'. 100 which may be located in a concave recess C² of the casing located beneath the nut of the bolt C.

A saw-cut b may be made in the casing, as shown in Figs. 7 and 8, and the kerf 105 filled by a strip b' soldered at each end to the casing within the slot so formed, by means of which greater flexibility may be given to the wall of the casing so operated upon. By reason of the said saw kerf, the 110 portion of the casing adjacent thereto will be rendered more yielding than the solid

part of the casing located at the opposite side of the gear. Consequently, a greater degree of pressure will be exerted against the side of the gear adjacent to the said 5 saw kerf than at the opposite side of the gear, which differential or varied degree or tension of the pressure may be regulated by the adjustment of the bolt C. A recess G³ may be made in the outer lateral face of 10 the parts G and G', which may contain oil or other suitable lubricant, and also a plug G² made of fiber or other desired material, which may serve to create additional friction of the parts in a lateral direction, and 15 at right angles to the pressure created by the bolt C, upon the casing being forced in an inward direction by means of the screw H.

A section of the glass wind shield O may 20 be inserted in and held by each of the members A and E by the employment of intermediate means, as an inclosing tube or framework F and intermediate packing A', preferably made of felt.

25 By means of the construction herein disclosed, the upper section of the wind shield may be positioned at any angle, or, if desired, folded down either frontward or rearward, and the said section will be securely held in any of the above-named positions 30 solely by the friction of the parts, and without the use of any screws or other extraneous fastening or clamping devices which ordinarily have to be used for this purpose.

35 It will be observed that the shell of the casing B is pressed in an inward direction both by the head of the bolt C and also by the heads of the screws H, a washer being interposed in each instance between the said 40 heads and casing, namely the washers C' and h. The screws H pass through the casing and a portion of the gears and are screwed into the remaining portion of the latter. The bolt C passes through a portion of the 45 casing and the gears and is screwed into the casing B. The bolt H moves in unison with the casing B, and the engagement therewith of the gears will not cause it to work loose, on account of the resilience of the washer, located between the bolt head and casing and 50 engaged with the latter, which is sufficient to overcome any torsional stress upon the bolt occasioned by the rotation of the gears, by creating a strain or pressure between the 55 head of the bolt and the threaded part of the casing in which the end of the same is entered, being thereby locked in the hinge and exerting a pressure of the casing on opposite sides of the gears.

60 The screws H move in unison with the gears and the engagement therewith of the casing will not cause them to work loose, on account of the resilience of the washers, located between the screw heads and casing 65 and engaged with the latter, which is suffi-

cient to overcome any torsional stress upon the screws occasioned by the rotation of the casing, by creating a strain or pressure between the heads of the screws and the threaded parts of the gears in which the 70 ends of the same are entered, being thereby locked in the hinge. In each instance, the screw and bolt heads serve to hold the hinge members under friction to retard the movement thereof, the threaded portions of the 75 bolt and screws serve to adjust the degree of friction, and the washers, which are locked or rigidly held to the hinge, serve to provide means to afford a positive resistance or obstacle to, and to prevent, the adjusting 80 screw heads H being turned, or working loose, by the movement of the casing; and also to the adjusting bolt head C being turned, or working loose, by the movement of the gears, whereby, as stated, either section of the shield may be securely held in the 85 adjusted position by the use of the said hinge alone.

Each rotary hinge member has an engaging peripheral edge, which edge is engaged 90 by the casing with a positive friction pressure action exerted against each opposite and outer side portion of the face of the members, the degree or tension of the same being adjusted in the manner described. On account of the dual concave construction of the 95 orifice of the casing, the said pressure is exerted in a series of radial lines located opposite each other and each running from the periphery to the center of each hinge 100 member.

It will be noted that the axes of the gear members or sections, one of which at least is adapted to roll about the other, and those of the casing B, which is also movable 105 around its axes, are concentric. Inasmuch as the casing incloses the said sections and lateral movement thereof as a whole is prevented by the inner edge of the flange thereof which is held by the casing and screws H 110 so as to abut the said sections in cases where the recesses G³ and plugs G² are not employed—whereby great solidity and strength is imparted to the device—it is manifest that 115 the desired friction between the casing and the sections must be produced by the yielding of the said concentric portions of the casing—owing to the flexibility secured by the use of the saw cut b—by the action of 120 pressing the said concentric parts of the casing and gears together by the pressure means comprising the screws H, at which points a greater amount of pressure is produced on the concentric portions of the side faces of 125 the gears, or those adjacent to the axes thereof than at the outer parts or peripheries of the same. The dished washers h located intermediate the casing B and the heads of the screws H, and which serve to carry the pressure to the casing, are relatively mov- 130

able so far as the said casing is concerned, but have, as stated, a fixed relation in respect to the said pressure means, whereby the efficiency and durability of the structure 5 is further enhanced and the parts are prevented from working loose.

It will be obvious to those who are familiar with such matters that many departures may be made from the specific construction and arrangement of parts shown 10 above (which discloses one form only in which the invention may be embodied) and yet the essential features of the invention be employed. I therefore do not limit myself 15 to such details.

What I claim as my invention, is:—

1. A hinge comprising a plurality of peripherally engaged hinge members formed with teeth on the outer edges thereof, a casing 20 for the hinge members, and means for creating friction between the hinge members and the casing by a transverse pressure of the casing against the peripheral teeth of the hinge members.

2. A hinge comprising a plurality of peripherally engaged hinge members formed with teeth on the outer edges thereof, a casing for the hinge members, and means for creating friction between the hinge members 30 and the casing by a transverse pressure of the casing against the peripheral teeth of the hinge members, and means for exerting a lateral pressure of the casing on the side face of a hinge member.

3. In a device of the class described, a hinge comprising a plurality of members A and E formed with peripheral gear teeth, one at least being adapted to roll about the other, a separate support F for each member 40 located at the inner portions of the gears, a common support and covering B for the said members having a flexible portion and located at the outer faces of the latter, the axes of the same being concentric with those of the hinge members, means comprising the abutting inner edge of the outer portion of the common support to prevent the latter from moving inwardly as an entirety, the said hinge members and the common 45 support being so respectively constructed and arranged that the latter shall be capable of approaching the former under pressure at the axes thereof, and means comprising a bolt H to produce, by the yielding at 50 the central part of the common support, a greater pressure of the same against the hinge members at the said concentric portions thereof than at the outer part or periphery of the same, whereby certainty of 55 action and great solidity and strength of the device are secured.

4. In a device of the class described, a hinge comprising a plurality of members

formed with peripheral gear teeth, one at least being adapted to roll about the other, 65 a separate support for each member located at the inner portions of the gears, a common support and covering for the said members having a flexible portion and located at the outer faces of the latter, the axes of the same 70 being concentric with those of the hinge members, means to prevent the common support from moving inwardly, as an entirety, the said hinge members and the common support being so respectively constructed and arranged that the latter shall be 75 capable of approaching the former under pressure at the axes thereof, and means to produce, by the yielding at the central part of the common support, a greater pressure 80 of the same against the hinge members at the said concentric portions thereof than at the outer part or periphery of the same, whereby certainty of action and great solidity and strength of the device are secured. 85

5. In a device of the class described, a hinge comprising a plurality of members formed with peripheral gear teeth, one at least being adapted to roll about the other, a separate support for each member located 90 at the inner portions of the gears, a common support and covering for the said members having a flexible portion and located at the outer faces of the latter, the axes of the same being concentric with those of the 95 hinge members, means to prevent the common support from moving inwardly as an entirety, the said hinge members and the common support being so respectively constructed and arranged that the latter shall 100 be capable of approaching the former under pressure at the axes thereof, and means to produce, by the yielding at the central part of the common support, a greater pressure of the same against the hinge members at 105 the said concentric portions thereof than at the outer part or periphery of the same, whereby certainty of action and great solidity and strength of the device are secured, in combination with means located intermediate the common support and pressure means and adapted in use to convey the pressure to the common support and to be relatively movable so far as the latter is concerned, but to have a fixed relation in 110 respect to the said pressure means, whereby the parts are prevented from working loose. 115

In testimony of the foregoing specification I do hereby sign the same in the city of New York, county of New York and State 120 of New York, this 21st day of March, 1910.

WILLIAM G. LE COMpte.
